UNITED STATES PATENT OFFICE

124,775

DESIGN FOR A DRESS ENSEMBLE
Anne Florek, Chicago, Ill.

Application November 27, 1940, Serial No. 96,887

Term of patent 3½ years

To all whom it may concern:

Be it known that I, Anne Florek, a citizen of the United States, residing at 2317 Kimball Avenue, Chicago, in the county of Cook and State of Illinois, have invented a new, original, and ornamental Design for a Dress Ensemble, of which the following is a specification, reference being had to the accompanying drawings, forming part thereof.

I claim:

The ornamental design for a dress ensemble, substantially as shown.

ANNE FLOREK,
